RITTENHOUSE M. SMITH, OF MOBILE, ALABAMA.

FILING DEVICE.

Application filed February 20, 1922. Serial No. 538,043.

The present invention relates to card filing devices.

The principal object of the invention is the provision of a device of the aforesaid type for filing cards in accordance with two kinds of data, which employs only a fraction of the space required in prior systems.

To this end the device comprises two series of index characters disposed at right angles to each other and means to support a card to be filed parallel to one series and opposite a character of the other series, the cards being disposed in overlapping relation to each other to permit a compact arrangement of cards in the file.

More specifically the invention comprises a container having two series of index characters disposed at right angles to each other, and a series of cards each having an indicator at its upper edge. The cards are filed in the container parallel to one series of characters and opposite a character of the other series. The characters of the first series are spaced so that there are several characters in a distance equal to the length of a card and means is provided for positioning the cards parallel to the series of characters with their indicators in line with a selected character of said series. For this purpose the cards and container may be formed with interengaging tongues and grooves.

The width of the container in the direction of the last-mentioned series of characters may be equal to the length of the series plus the length of one card. Thus, if there are ten characters in the length of one card, this additional space may be utilized for another series, such, for instance, as for indicating the months of the year and the series is thirty characters long, then the width of the container will be equal to the length of four cards. and although the width is only four cards it will be seen that thirty cards may be filed and spaced in this length.

Another feature of the invention resides in the provision of a movable index slideable along one series of index characters.

Another feature of the invention resides in the novel form of filing card employed.

Another feature of the invention resides in the provision of a means of obstructing the withdrawal of the card from its position in the cabinet.

Other features of novelty and objects of

the invention will be apparent from the description taken in connection with the drawings in which:

Figure 1 is a perspective view on a reduced scale of a filing device constructed in accordance with the present invention;

Figure 2 is a partial sectional elevation, showing the finger of a card positioned in a slot;

Figure 3 is a fragmentary perspective view of a portion of the container;

Figure 4 shows one form of the card attachment;

Figure 5 shows a modified form of card;

Figures 6, 7, and 8, respectively, show modified forms of the card attachment; and

Figure 9 shows a modified form of indicating tab.

Referring to the drawings it will be seen that the filing device is shown as comprising a rectangular shell consisting of the four side members 15, 16, 17 and 18, the upper side of this shell being open. Preferably, the lower side of the shell is closed as by a bottom 19, although this bottom is not absolutely necessary. Spaced from the bottom and the lower edges of the side pieces of the shell is a grid comprising spaced parallel members or bars 20, the spaces between the same being indicated by the numeral 32. In the form of the invention shown the grid is held spaced from the lower edges of the shell by the spacing blocks 22. It will be obvious that the spacing blocks may vary in height so as to position the grid as desired relative to the lower edges of the shell. Any suitable means may be provided for holding the grid against movement toward the top of the shell. As shown for this purpose flat members 23 are secured to the sides 16 and 15 on the interior thereof.

In the embodiment of the invention shown the longitudinal space indicated by each of the index characters for months and days of the month preferably terminates on the center lines of adjacent bars 32 so that the indicating end of each card for that index character is between the ends of the indicating space and thus the fact that it is indicated by that character is unmistakable. It will be apparent, however, that the invention is not limited to having the spacing of the characters equal to that of the bars providing only one transverse slot between adjacent bars for all cards indicated by the corresponding index characters since the

functions and advantages of the invention in properly spacing in series and clearly indicating the cards for each index character could be secured by having a series of adjacent slots designated by a single index character.

The present invention employs a special form of card. Thus, as clearly shown in the drawings, a positioning finger 35 projects from the lower edge of the card 33 and is adapted to be disposed in a slot 32 between the bars 20, and thus properly position the card. At its opposite or upper edge, the card is provided with an indicator. In the form shown this indicator projects above the upper edge of the card as illustrated at 34. Preferably, the positioning finger and indicator are provided on a reinforcing strip 36 secured to the edge of the card. In some instances it is desirable to have the indicator of different colors or forms. To this end the upper end of the binding piece 36 may be threaded as indicated at 37 and the indicator 34 provided with a ferrule internally threaded so that it may be screwed on to the upper edge of the binding strip. In this manner various forms of colored indicators 34 may be employed.

Another form of the card is illustrated in Figure 5. In this modification two positioning fingers 35 project from the lower edge of the card and preferably these fingers are integral with a reinforcing strip on the bottom edge of the card, and this strip may be integral with the strip 36 at the vertical edge of the card. The card may be sufficiently pliable to allow the second finger to be inserted after the first finger is in place by bending the card slightly to allow the finger to slide through the slot.

Figure 6 shows a modified form of the positioning finger having two tongues 35 on the same side of the finger. This form of card may be used when two grids are employed.

Figure 7 shows a positioning finger which is curved to prevent direct vertical withdrawal of the card from the grid.

Figure 8 shows another modification of the positioning finger having a T-shape end, the projections 35 extending at right angles on each side of the finger.

The object of these forms is to obstruct the withdrawal of the finger from the grid, thus preventing the card from being unintentionally moved out of position. To this end the finger is either broadened at one or more points transversely to the bars of the grid to a width which will cause the broadened point to resist being raised through the slot, or the finger is curved transversely to the bars of the grid. One illustration of such a curve is shown in Figure 9, but the invention is not limited to any particular location of the curve along the finger,

or to any particular type of curve or projection.

When the card is positioned in the grid, and a broadened portion of the finger has been lowered through the slot, and it is desired to remove the card, the member may, if the finger is at any point below the bars too broad for passing upwardly through the slot, be slightly turned so as to permit the finger to pass upwardly through the slot.

In employing the present invention the card 33 is filed between a pair of partitions parallel to the same and with its positioning finger 35 in a slot 32 such as will bring the indicator 34 in line with one of the characters of the series extending parallel to the partitions. In the form of the invention illustrated one series of characters, namely that extending perpendicular to the bars 20 consists of members 1 to 31, to represent the days of the month and also the abbreviations for the twelve months of the year.

The other series of characters is shown as the letters of the alphabet. These letters are shown on the upstanding tabs on the partitions illustrated in Fig. 1. It will be understood, however, that the invention is not limited to either of the forms of character shown. With the characters shown the cards may be filed alphabetically according to the name or subject matter, for example, and also filed in accordance with the date, say the date that the matter is to be brought up for action. The cards coming up for action during the current month may be filed in line with any of the characters from 1 to 31. Matters coming up during future months will have their cards filed under one of the months indicated by the month characters 44. In case the month characters are too close to the right hand end of the partition to permit filing of the card with its face forward, the card may be withdrawn and reversed so as to bring the index finger directly in line with the month character.

Preferably, an index is slidably mounted to move along the series of characters 29 on the top edge of the container. As shown, this index comprises a U-shaped member having legs 42 one of which appears in Fig. 1 while the other lies behind the index scale, straddling the channel bar and a projection 41 struck up from the base of the U member providing the aperture 43 through which the characters of the series may be viewed. This index may be moved along to indicate the current day of the current month and all cards in line with the index will be taken out at the beginning of each day. It will be understood that the index numerals on the side of the box and on the partitions are in alignment parallel with the sides of the box. A similar index 41 may be provided as indicated in Figure 1 and positioned at the left of the first-men-

tioned index so that the cards may be positioned for the days of the subsequent month up to the day corresponding to the current day of the current month. It will be noted 5 that the grid in use is in fixed position in the container and serves as the support for the cards and that the facing sides of the adjacent transversely extending bars 20 form facing spaced longitudinal abutments 10 on opposite sides of slots 32 to cooperate with a downward projection from a card thus preventing longitudinal displacement of the cards when in adjusted position. The longitudinal distance apart of the adjacent 15 slots and the adjacent pairs of abutments, the length of the longitudinal space indicated by each of said index characters and the distance between adjacent index characters of the series constitutes in each case 20 only a small fraction of the normal length of the well-known cards ordinarily used in card indexes. The primary purpose and function of this structural arrangement is to permit any selected set of cards of like 25 size to be placed in a predetermined longitudinal position in the container with a visible predetermined part of each card of the set, for example its upper end edge or an upwardly projecting indicator, in the same 30 transverse plane as other cards of the set and to space the adjacent sets longitudinally of the container by only a small fraction of the length of the card, those of one set partly overlapping those of a number of the 35 next succeeding sets in the series, thus effecting a great reduction in the necessary length of the container to distinctly exhibit and identify a given number of sets of cards. The arrangement is furthermore such that 40 when a set of cards has been placed in adjusted position as above indicated, and held against longitudinal displacement, the said visible predetermined parts of each card in the set will be between the transverse planes 45 through the ends of a space indicated by one of said longitudinally arranged index characters and thus that set will be distinctively indicated by that character. In the particular form shown, each slot or pair of facing abutments is between the ends of the space indicated by an index character and the predetermined distinctive visible parts 50 of the cards are directly above them and also between said transverse planes, but it is of course obvious that this specific form is not necessary to secure the functions and results stated. The several partitions permit 55 arrangement of the cards according to subject matter or names, while the slotted grid 60 enables one to file the cards between the

partitions according to date, thus providing for longitudinal as well as transverse separation and classification of a large number of cards. It should be noted that the structure of the container is very simple embodying a few parts and none likely to get out of order and that a series of simple physically similar and indistinguishable cards may with the greatest ease be placed in it in such positions that by this mere location of a particular card in the container two characteristics of the data on that card may be determined from the index characters. In other words, the cards are distinctively classified in two respects, notwithstanding the fact that they are assembled in a minimum of space with cards of different classifications in contact with each other and all are visible at one time. No special attachments to distinguish cards are necessary since the entire operation consists merely in placing the cards in position by hand and removing them by hand when desired.

As shown by the above drawings, the projection 35, when below the slot and bars, obstructs the upward passage of the finger 36, so that though the card may be lifted upwardly, it retains its specified place in the device.

It will be understood that although the invention has been described as a card-filing device, the term card is used to apply to any sheet material, envelope, book or folder.

Although a specific form of the invention has been described in detail, it is to be understood that the invention is not thus limited, but includes modifications and changes which come within the scope of the appended claim.

Having thus described the invention, what is claimed as new and desired to be secured by Letters Patent, is:

A card filing device, comprising in combination a grid of spaced parallel bars, a pair of parallel side members supporting said grid, disposed perpendicular to said bars at opposite ends thereof, one of said members being provided with a series of index characters each vertically above a space between two grid bars, and cards each having aligned with a vertical edge thereof an indicator and a positioning finger, said positioning finger fitting between any two grid bars, a portion on said finger being out of alignment with said vertical edge to prevent its ready removal from between the grid bars.

In witness whereof, I have hereunto set my hand, this 16th day of February, 1922, at Mobile, Alabama.

RITTENHOUSE M. SMITH.
